SNOW THROWER

Alvin Romin, Jr., Oak Lawn, Ill., assignor to Sunbeam Corporation, Chicago, Ill., a corporation of Illinois

Filed Apr. 8, 1968, Ser. No. 11,343

Term of patent 14 years

U.S. Cl. D35—2
Int. Cl. D15—05

FIG. 1 is a front perspective view of a snow thrower embodying my new design;

FIG. 2 is a rear perspective view thereof; and

FIG. 3 is a side elevational view thereof.

Broken lines are shown for illustrative purposes only.

The characteristic features of my design for a snow thrower reside in the rearwardly extending, platform-mounted trailing wheels and the forwardly projecting skids, all as shown.

I claim:

The ornamental design for a snow thrower, substantially as shown and described.
